COLLAPSIBLE TUBE CAP HOLDER

George W. Schumaker, Indianapolis, Ind.

Application July 29, 1939, Serial No. 287,189

10 Claims. (Cl. 221—60)

This invention relates to means interchangeably employed in conjunction with collapsible tubes such as tubes containing shaving cream, tooth paste, etc., for the purpose of receiving and holding the tube closure cap so as to prevent loss of the cap by dropping it on the floor or the like when the cap is removed from the tube receiving nipple.

An important advantage of my invention is that the device may be readily removed from an empty tube and attached to a filled tube so that it may be used over and over again. A further advantage of the invention is that it is embodied in a unit that may be separated from the tube rather than having to be incorporated as a part of the tube when the tube is made.

A further important advantage of the invention is that the cap is positively removed and rigidly retained in the removed position by engagement within a housing that is rockably attached to a second member in turn detachably secured to the tube. The invention may be employed throughout a wide range of tube nipple threads and nipple lengths as will hereinafter be more fully explained.

These and many other objects and advantages of the invention will become apparent to those versed in the art in the following description of one particular form of the invention as illustrated in the accompanying drawing, in which

Fig. 1 is a side elevation of a structure embodying the invention as applied in a closed position to a tube;

Fig. 2, a similar view in partial section with the cap removed from the tube;

Fig. 3, a side elevation 90 degrees from that shown in Figs. 1 and 2 and showing the cap housing rocked to one side;

Fig. 4, a central vertical section through the structure embodying the invention in modified form;

Fig. 5, a top plan view of the modified form;

Fig. 6, a central vertical section of a further modified form of cap and housing; and

Fig. 7, a central vertical section of the form shown in Fig. 1.

Like characters of reference indicate like parts throughout the several views in the drawing.

I form a cup-like housing 10 internally threaded and having two extending, diametrically opposed legs 11 and 12. These legs may be separately made and attached to the housing 10 but are herein shown as constituting integral parts of the housing. The lower end of each leg 11 and 12 is turned inwardly one toward the

other to enter bores formed in opposite sides of a ferrule 13. In the form herein shown, the bores are carried in bosses 14 and 15 and the inturned ends of the legs 11 and 12 are rockably carried within those bosses so that the housing 10 may be rocked over the end of the ferrule 13 and to either side as desired.

The ferrule 13 has a slightly concave under surface 25 and its internal bore is screw-threaded, preferably tapered from a larger diameter 10 at the under side to a smaller diameter at the top end. The external periphery of the ferrule 13 is also threaded. The internal threads of the ferrule 13 are formed to fit approximately the threads 16 appearing on the outside of the tube 18 nipple 17. Since the nipple 17 is generally made out of a comparatively soft metal, and the ferrule 13 is internally tapered, these internal threads will engage the threads 16 when the ferrule 13 is screwed thereover to permit the under face 20 of the ferrule 13 to be brought down snugly against the end of the tube 18 regardless of the exact conformation of one set of threads with the other. The vertical height of the ferrule 13 is made to be equal at least to the length of the 25 longest nipple 17 normally found on the tube 18. In the form herein shown, Fig. 2, the nipple 17 is slightly shorter than the ferrule 13.

A cap 19 is formed to screw-threadedly engage over the external threads of the ferrule 13 and 30 carries a knurled peripheral surface 20 to be engaged by the operator's thumb and fingers as a means for turning the cap either to seat it on the ferrule or to remove it. The surface 20, of course, may be varied in design. Above the engaging surface 20, the cap 19 is externally screw-threaded so that this portion of the cap may engage with the internal threads of the housing 10. The cap 19 can not be removed from the ferrule 13 without causing the cap to be carried 40 upwardly in the housing by continued rotation of the cap.

When the cap 19 is thus carried within the housing 10, Fig. 2, the housing 10 may be rocked to one side by reason of the pivotal connections 45 of the inturned ends of the legs 11 and 12 with the ferrule 13 whereby the housing 10 and its cap will assume some such positions as indicated in Fig. 3. In this case, the tube is then free to discharge its contents and at the same time the 50 cap 19 is held available to be re-entered over the ferrule 13 to close off the tube opening.

As indicated in Fig. 7, the cap 19 is permanently screw-threadedly engaged with the housing 10 so that the housing 10 may not be rocked to 55

either side of the cap 19 when the cap is seated on the ferrule 13. In this structure, the cap and housing are each made to be sufficiently long to have the housing receive the cap in its open position and hold it at a sufficient distance above the ferrule 13 to permit the housing and the cap therein to be rocked to one side for discharge of the tube contents. Any slight misalignment between the two sets of threads—housing and 5 external cap threads, and ferrule and internal cap threads—may be compensated for by elasticity of the legs 11 and 12 permitting sufficient shifting between the housing and ferrule. The two sets of threads would have the same pitch 10 and fit, as indicated, rather loosely between the 15 engaging members.

Should it be desired to have the seated cap 19 free of engagement with the housing 10 in respect to the cap external threads, it will be noted 20 that when the cap 19 is seated on the ferrule 13, the housing 10 may be rocked to either side of the cap. This means that the housing 10 must be initially rocked to its central upper position to receive the cap 19 when the cap is to be removed from the ferrule 13. In order to insure 25 initial alignment which might be overlooked by the operator, a pilot pin 21, Fig. 4, is centrally secured to the cap 19 to extend upwardly therefrom and loosely through an opening in the housing 10 to serve as a guide. In the form herein shown, this pin 21 constitutes an integral part 30 of the cap 19 and is of sufficient length to permit the seating of the cap 19 and still have an upper portion of the pin 21 entered in the bore 35 through the top of the housing 10 so as to prevent rocking of the housing 10 until the cap 19 has been carried upwardly into the housing and removed from engagement with the ferrule 13.

It is to be noted that in the form of Fig. 4 there 40 is sufficient freedom in the fit of the external threads of the cap 19 with the internal threads of the housing 10 as will permit the engagement of the cap therewith before it is entirely removed from engagement with the ferrule threads so that the simultaneous engagement of the two sets of 45 threads will not cause binding of the cap 19. Accuracy of fit in the two sets of threads is not required. The principal requirement is that the cap may be so engaged as to cause its elevation 50 within the housing 10 upon lifting from the ferrule 13.

Referring to the modified form illustrated in Fig. 6, this form would be used either with or without the pilot pin 21. When used without the 55 pin as illustrated, the upper end of the cap is made conical so that when the housing is rocked to its central position over the cap, the housing will be held between the operator's thumb and fingers to have the thumb and fingers extend on 60 beyond to grip the modified form cap 26 to loosen the cap and turn it about the ferrule 13 and thereby cause the cap to advance into the housing. The conical upper cap end will enter the housing and center it over the cap as the cap 65 advances therein, so that the conical end serves as a centering pilot. The housing may be lengthened to receive this modified cap 26 and be conically shaped itself at the upper end.

While I have herein shown and described my 70 invention in the one best form as now known to me, it is obvious that structural changes may be employed without departing from the spirit of the invention and I, therefore, do not desire to be limited to that precise form beyond the 75

limitations as may be imposed by the following claims.

I claim:

1. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the entrance to the ferrule, and screw-threads carried by said member engaging with the threads of said housing for carrying the member into the housing. 15

2. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the entrance to the ferrule, and screw-threads carried by said member engaging with the threads of said housing for carrying the member into the housing, said legs spacing said inner housing end from said outer ferrule end that distance as will permit clearance of said member over said ferrule when the member is retracted on the housing threads following disengagement of the member threads from the ferrule threads. 20

3. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the entrance to the ferrule, and screw-threads carried by said member engaging with the threads of said housing for carrying the member into the housing, and pilot means centering said member in said housing. 25

4. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the entrance to the ferrule, and screw-threads carried by said member engaging with the threads of said housing for carrying the member into the housing, and pilot means centering said member in said housing, said pilot means retaining said housing in its central position of alignment with said member when the member is seated on said ferrule. 30

5. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the entrance to the ferrule, and screw-threads carried by said member engaging with the threads of said housing for carrying the member into the housing, and pilot means centering said member in said housing, said means consisting 35

of a member portion extending from the member and rotatably guided by the housing.

6. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the entrance to the ferrule, and screw-threads carried by said member engaging with the threads of said housing for carrying the member into the housing, and pilot means centering said member in said housing consisting of an elongated portion of said member carrying said cap-housing threads thereover.

7. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the entrance to the ferrule, and screw-threads carried by said member engaging with the threads of said housing for carrying the member into the housing, and pilot means centering said member in said housing, said means consisting of a member portion extending from the member and rotatably guided by the housing, comprising a pin extending through a bore in the housing.

8. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the

entrance to the ferrule, and screw-threads carried by said member engaging with the threads of said housing for carrying the member into the housing, and pilot means centering said member in said housing, said means consisting of a member portion extending from the member and rotatably guided by the housing consisting of a conical upper end on said member.

9. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the entrance to the ferrule, and screw-threads carried by said member engaging with the threads of said housing for carrying the member into the housing, and finger engaging means on said member extending beyond the member housing threads.

10. For a collapsible tube having an outlet nipple, a ferrule for entering over and engaging the nipple, a housing, legs carrying the housing and hingedly connected with the ferrule to space the housing beyond the outer end of the ferrule, said housing being open at its inner end and being screw-threaded, a closure member screw-threadedly engageable with said ferrule to close off the entrance to the ferrule, and screw-threads carried by said member engaging with the threads of said housing for carrying the member into the housing, said member-housing threads remaining in continuous engagement, and said legs and their connections with said ferrule providing sufficient freedom for simultaneous travel of the closure member between its respective housing and ferrule threads.

GEORGE W. SCHUMAKER. 40
